Specification for Design.

Patented Feb. 2, 1915.

Application filed November 5, 1914. Serial No. 870,518. Term of patent 7 years.

To all whom it may concern:

Be it known that I, VICTOR GUINZBURG, a citizen of the United States, and a resident of the city, county, and State of New York, (and whose post-office address is 725 Broadway, in said city,) have invented a new, original, and ornamental Design for Bathing-Caps, of which the following is a specification.

Reference is to be had to the accompanying drawing, in which—

cap, showing my design; Fig. 2 is a side elevation of the same; and Fig. 3 is a rear elevation of the same.

I claim:

The ornamental design for a bathing cap as shown.

Signed at the city, county and State of New York, this 23rd day of October, 1914.

VICTOR GUINZBURG.
